Fig. A.

Constant J. Krizanovsky Inventor:
by his Agent:
Philip J. Kennedy, Rue St. Charles,

UNITED STATES PATENT OFFICE.

CONSTANT J. KRYZANOWSKY, OF MOUNT WASHINGTON, MARYLAND, ASSIGNOR TO THE CROWN CORK AND SEAL COMPANY OF BALTIMORE CITY, OF BALTIMORE, MARYLAND, A CORPORATION OF MARYLAND.

BOTTLE-CAPPING MACHINE.

Application filed May 26, 1917. Serial No. 171,089.

To all whom it may concern:

Be it known that I, CONSTANT J. KRYZANOWSKY, a citizen of the United States, residing at Mount Washington, county of Baltimore, and State of Maryland, have invented certain new and useful Improvements in Bottle-Capping Machines, fully described and represented in the following specification and the accompanying 10 drawings, forming a part of the same.

This invention relates to improvements in bottle-capping machines.

Users of capping machines of the sort in which crowns are fed to the capping heads 15 by hand, frequently desire to substitute automatic crown feeds without going to the expense of acquiring an entirely new machine.

It is one of the objects of this invention to provide automatic crown feeding apparatus 20 which may be readily and inexpensively attached to and combined with a capping machine originally made for hand feed to form a complete automatic crowner.

In the use of bottle-capping machines, it 25 is more or less frequently desirable to disassemble or remove the various parts for the purpose of cleaning, changing the style of crown used, removing mutilated crowns and the like. In machines of this sort, as heretofore known, such disassembly and removal 30 has been inconvenient and attended with a substantial loss of time. A further disadvantage in capping machines as heretofore known, has been the fact that the crown 35 cage and selecting dial could not be removed without disturbing the crowns held in the storage channel, and in cases where this channel has been formed by a relatively movable member, as, for example, the cage 40 itself, there has been the additional disadvantage that the crowns in the channel were subjected to the friction of the moving member.

It is a further object of the present invention to provide a bottle-capping machine 45 in which crowns held in the storage channel are not subjected to the friction of moving parts and are not disturbed by removal of the crown cage.

With these general objects in view the invention consists in the combinations, details of construction and arrangements of parts 50 which will first be described in connection

with the accompanying drawing and then more particularly pointed out.

In the drawings—

Figure 1 is a view in side elevation of a bottle-capping machine constructed in accordance with this invention;

Fig. 2 is an enlarged front view of the 60 upper part of the machine;

Fig. 3 is a vertical cross-sectional view; and

Fig. 4 is a cross-sectional view taken on the line 4—4 of Fig. 3.

The capping head 10 shown in the present embodiment, which is of the type that is reciprocated to and from the bottle to be capped, has an arm 11 which is secured to the top of a reciprocating rod or plunger 70 12 enclosed within a hollow standard 13 extending upwardly from the base 14. This plunger is connected by a pitman 15 with the crank pin on a crank disk fixed to a shaft 16 which is in turn connected with the drive 75 shaft by a clutch of the type that causes one cycle of the driven shaft for each actuation of the clutch. The clutch is operated by a treadle 17. Extending out from the top of the standard 13 is a bifurcated guide bracket 80 18 between the arms of which a web 19, formed integral with the head 10, slides as the head moves up and down.

The bottle 20 to be capped rests on a table 21 at the top of a cylindrical casing 22 which 85 has a bearing in a bracket 23 extending out from the standard 13. To raise and lower this table to adapt the machine to bottles of different sizes, i. e., quarts, pints, etc., the cylindrical casing 22 is provided at the 90 bottom with a screw 24 in threaded relation with a sleeve 25 carried by a bracket on the base 14. By turning the casing the table is raised or lowered, a set screw 27 serving to lock the parts in any desired position. The 95 casing 22 preferably contains compensating mechanism of any suitable type for taking care of slight manufacturing variations in the dimensions of the bottles being capped.

All the above described features are well 100 known in the art and need no further description.

The hopper here shown as an example 28 has central and rear bosses 29, 30, for the reception of the shaft, and a central wall 1 105 which leaves a passageway 32 for the crowns

to pass to a circular front chamber 33, which is closed by the crown cage 34. This cage, which is rotated as hereinafter described, has a flat, annular flange 35 to which is secured the selecting dial. This latter is of a construction well known in the art and comprises a ring 36 carrying a plurality of equally spaced pins 37 larger at the base than at the top. These pins are so designed and so spaced that a crown presented to them can pass between the same only when faced in one way, so that all the crowns passing to the capping head are properly faced. To agitate the crowns in the bottom of the hopper chamber the selecting dial carries one or more paddles 38. Crowns entering the hopper chamber 33 in passageway 32 are tumbled about by the paddles, some of them then being lifted over the edge of the dial into the cage, where further tumbling by the rotation of the cage presents them to the selecting dial and such as are properly faced pass between the pins.

The invention in its entirety includes means for storing the selected crowns, such that the crowns stored thereby are not disturbed by the removal of the crown cage and selecting dial, and are not in contact with any relatively moving parts. Although this may be accomplished in various ways, the construction illustrated comprises a channel forming ring 39 approximately L-shaped in cross-section, secured to a flat annular portion 40 of the hopper face and centered thereon by an annular rib 41. It will be apparent from Fig. 3 that this ring, in conjunction with the hopper face, forms a channel 42 surrounding the selecting dial for the reception of crowns which pass between the pins of the dial. The face of the storage ring is concentric with the flange of the crown cage and the inside diameter of the storage ring is greater than the outside diameter of both cage and dial. As a result, the latter may be removed regardless of the storage ring and without in any way disturbing the same or the crowns stored in the channel formed thereby. In addition, it is noted that the storage channel is formed by stationary parts, so that the crowns therein are not subjected to the friction of moving members.

As the cage and dial rotate, crowns passing between the pins as before described, drop into the storage ring and slide down the same until they reach an exit passage 43 at the bottom, through which they pass into the delivery chute. When the chute is full the crowns accumulate in the left hand side of the ring as well as in the right hand side.

There is provided means for attaching the hopper and crown feeding apparatus to the crowning head to be carried thereby. This may be accomplished in various ways. In

the form illustrated, the head top nut 44 has formed integral therewith an upwardly extending column 45 to which a depending cylindrical portion 46 of the hopper is clamped by means of bolt 47. There is also provided means for making the position of the hopper adjustable with respect to the head. While this end may be attained in various ways, in the present embodiment the column 45 is threaded to receive an adjusting nut 48 bearing against the hopper. By turning this nut the hopper can be relatively raised or lowered in order to line up the chute with the head opening.

Means is provided for partially compensating for the weight of the hopper and head on the column 12. In the constructions embodying the invention to the best advantage, a balance spring is provided. While such a spring is capable of various constructions, as illustrated, it comprises a volute band 49 of flat, spring material, bearing at the top against the arm 11 of the head and centered on the column by a tipped washer 50 carried by the top of the standard 13. A spring of this construction is advantageous in view of the restricted space and the considerable movement of the parts. Furthermore, it is self-protecting, as it is of such construction as to prevent a workman from crushing his fingers, for example, as would be possible with springs of other forms.

There is provided means for causing rotation of the hopper shaft which, as herein-after appears, drives the crown feeding apparatus in an effective manner and at the same time means of such character that extensive and complicated changes are not necessary in combining the automatic feed with originally hand fed machines. In structures embodying the invention to the best advantage, the hopper shaft is normally caused to rotate by the movement of the hopper but is allowed to remain relatively stationary in case a defective crown or foreign matter becomes wedged between the moving parts of the feed.

While such driving means is capable of a wide range of constructions, in the exemplification shown, pinned to the hopper shaft 51 is an arm 52 having a pivotal connection with a vertical connecting rod 53 which has a sliding bearing in a bracket 54 extending out from the standard 13. To normally hold the rod 53 from vertical movement a coil spring 55 is provided which bears against the bracket 54 and against a collar 55' adjustably secured to the rod by a thumb nut 56. On the down stroke of the head and hopper, the spring normally causes the rod 53 to remain stationary, thus causing arm 52 to swing, which in turn rotates the hopper shaft through an angle of about 60°. If, however, the wedging of defective crowns or other substances between the

moving and stationary parts of the feed tends to oppose rotation of the shaft, the rod 53 is forced downward against the spring and the shaft remains rotatively stationary. The tension of the spring 50 is adjusted as desired by moving collar 55' up or down on the rod.

There is provided means for rotating the crown cage and selecting dial by the movement of the hopper shaft just described, and at the same time permitting the cage to be independently rotated. In constructions embodying the invention to the best advantage, this is accomplished by a ratchet connection between cage and shaft. While such connection is capable of a wide range of constructions, in the embodiment illustrated, on the front end of the hopper shaft enclosed within a circular chamber 57 formed by the cage, is a ratchet 58 which has a clutch connection with a clutch collar 59 permanently pinned on the shaft. This clutch is of the two jaw dog type.

The cage 34 has a long hub 61 bearing on a shaft bearing hereinafter described, and having no positive connection with the other parts of the machine, is freely rotatable on its bearing. Fastened to the cage is a spring-pressed pawl 60 set in a direction 30 against the teeth of the ratchet. As a result of this construction, each time the ratchet is rotated by the shaft, a positive impulse is delivered to the cage which gives it a movement of about 60° after which it is carried 35 from a half to three quarters of a revolution by its own momentum. This movement of the cage and dial which moves with it, feeds the crowns as above set forth. As the cage is rotatable independently of the ratchet and shaft, it may be turned by hand when desired.

There is provided means whereby cage and dial are readily removable from the machine and from the shaft. While this end may be attained in various ways, in the form shown, on the front face of the ratchet, which, it will be observed, holds the cage onto the shaft, is pivoted a locking plate 62. A portion of this plate is cut out and bent away 50 to leave a pear-shaped opening 63, the cut-away portion serving as a handle 64. The small end of this opening is smaller than the shaft and the large end is larger. The end of the shaft is formed with a groove 65 and, when in locking position, the small end of the pear-shaped opening of the locking plate straddles this groove, thus holding the ratchet on the shaft, when, however, the locking plate is swung on its pivot 66 the large portion of the pear-shaped opening is brought up into a position to clear the shaft, thereby permitting the ratchet with the cage and dial to be slipped off the end of the shaft.

To hold the locking plate in position while

the machine is in operation, the plate is split, as shown at 67, Fig. 2 and is slightly bent to obtain a spring action which presses a small knob 68 formed in the plate into a corresponding indentation in the face of the ratchet. The ratchet is retained as a unit with the cage when the parts are removed, by a front plate 69 secured to the cage by screws 70, enclosing the chamber which holds the ratchet.

Means is provided for preventing any oil for the hopper shaft from reaching the crowns. Although capable of various constructions, in the exemplification shown, the shaft is enclosed in a long bearing 71 extending from the rear end of the shaft to the clutch collar. This bearing is carried by the rear and central bosses of the hopper and has a circular flange 72 by means of which it can be secured to the hopper. Cut in the inside of this bearing is a recess 73 opening directly on the shaft and connected by a passage 74 with an oiler 75 located at the outside of the cage. It will be seen that oil delivered to the shaft cannot drip down into the hopper or cage because the shaft is completely enclosed by the bearing 71 and the long overlap of the cage hub 61.

There is provided means whereby the throat guide, having a connection with the crown delivery chute, is readily attachable to the head of an existing machine and at the same time means whereby this throat guide and its associated parts are readily removable from the head. Although capable of a wide range of constructions, that employed in the present embodiment includes a throat guide nut 76 threaded to be received by the threaded end of the head 10. The throat guide 77 has cast integral therewith 100 a curved chute portion 78 which forms a connection between the chute proper and the throat guide. This curved chute portion is completed by a throat guide cover 79 which is secured to the crown platform 80. In this latter is an opening of a size to pass a crimped crown but to hold an uncrimped one, the bottom of the member 80 being flared outwardly, as shown in Fig. 3 to serve as a bottle guide. The crown platform and cover 80 are carried by the throat guide, as hereinafter described. The throat guide is removably attached to the nut 76 by a bolt 81 which passes through a split boss 82 formed on the throat guide, and engages a groove 83 formed in the nut 76. This bolt has an enlarged end 84 from which extends a curved pin 85, and a portion of the bolt is cut away as at 86 opposite the groove. The parts are tightened by a vise-handled nut 87.

By turning this latter member, the parts are locked in place, the pin or arm 85 bearing on the chute to prevent the bolt from turning. To remove the throat guide and associated parts, it is only necessary to loosen 130

4
nut 87 and turn the bolt until the cut away portion allows it to clear the stationary nut 76.

There is provided means whereby the 5 crown platform and the throat guide cover, which it carries, can be readily moved away from the throat guide for removing mutilated crowns, and the like. While this may be attained by numerous constructions, in 10 the form illustrated the crown platform is pivotally suspended from bolt 81 by two arms 88. On the side of the throat guide across from the hinge is a bifurcated lug 89 carrying a pin 90 on which is pivoted a latch 15 91, the finger of which engages a pin 92 carried by a bifurcated lug 93 on the crown platform. When the member 91 is unlatched, the crown platform and cover 80 can be swung on the hinge away from the 20 throat, thus giving access for removal of crowns.

Enclosed within the lower end of the head is the crowning throat which comprises a thin frustro-conical split ring 94 held in 25 place by keys 95 and backed by a ring 96. Also enclosed within the head is a knock-out plunger 97 pressed downwardly by a coil spring 98 bearing against the head top nut 44 and against a collar 99 formed on the 30 plunger. This collar also serves as a stop to limit the downward movement of the plunger. Its upward movement is limited by the bottom of a recess 100 formed in the head top nut 44 and in which the end of the 35 plunger moves. When the head descends to the waiting bottle the plunger is forced up by the bottle until stopped by the limitation on its stroke. In this position the cap is in such relation with respect to the capping throat as to allow the latter to bend in 40 the cap skirt thereby crimping the cap onto the bottle. And during this capping the cap and bottle are positively held in place by the then stationary plunger 97. As the head 45 ascends after capping, the spring forces the plunger down against the bottle to act as a knock-out and prevent the bottle from being lifted with the head.

There is provided means whereby the 50 chute from hopper to crown is readily removable. While this may be obtained by various constructions, in the embodiment shown, the delivery end of the storage ring registers with the top of a simple vertical chute 102 secured to a lug 103 on the hopper by a single thumb screw 104. The lower end of this chute has a slip fit into the separate curved chute portion 78, already described. This permits the ready removal of the curved 55 portion from the vertical portion and the latter is also readily removable by merely loosening nut 104.

Means is provided for stopping the flow 60 of crowns in case a mutilated crown is being received from the crown platform, or for

other reasons. Such means is capable of a wide range of constructions. In the present instance a wire stop 105 is bent around a portion 106 stuck out from the back of the chute. The lower end of the wire has a 70 single loop and the end is bent in the form shown in Fig. 3. To stop the flow of crowns, this wire end is inserted through a hole 107 in the back of the chute so as to extend into the path of the descending crowns. To re- 75 move the stop, this end is withdrawn and is held in place against the back of the chute by the spring action of the wire.

The operation of the machine will be clear 80 from the foregoing description. It has been stated that the cage (carrying the dial) is independently rotatable. Such a construction is convenient for various reasons. For example, when just starting a crowning operation, the crowns may be fed without operating the machine as a whole, by merely 85 manually rotating the cage. This is continued until the first crown reaches the capping head, whereupon the power is applied and continued feeding is accomplished by 90 the automatic rotation of the cage, as above described.

It is noted, in addition to the various novelties of the complete device, that the automatic feed and associated parts are combinable with existing machines with very little change in the latter. If this combination is made, the originally hand fed machine is provided with the head top nut 44 having the upper holding column 45 in place of the cap nut originally topping the head; the counterbalance spring is added; the bracket 54 for the drive mechanism is substituted for the original crown cup and the throat holder nut; and, lastly, the new crown plunger and throat are substituted. All of these substitutions and additions are easily and readily made.

What is claimed is:

1. In an apparatus for feeding crown, 110 the combination, with a hopper, of means for forming an annular storage channel carried by said hopper, a crown cage and selecting dial secured to each other and insertable into and removable from the central opening of the annular storage means, said crown cage and dial being arranged to deliver crowns to the storage channel, a chute arranged to conduct away crowns from a low point of said storage 115 channel, a shaft, means for rotating said shaft, a clutch member fixed to the shaft, a clutch member removable with the crown cage and dial, and means carried by the crown cage for engaging the removable 120 clutch member.

2. In a bottle capping machine, and in combination a hopper, a cage, a shaft for rotating the cage, a tubular shaft casing 125 extending through the hopper and into the

cage and provided with an oil channel, a tubular portion on said cage telescoping said shaft casing and rotatable thereon, said tubular portion of the cage having an oil channel for delivering oil to said first named channel.

3. In an apparatus for feeding crowns and the like, in combination with a hopper, a hopper shaft, a crown cage and selecting dial, a ratchet having a clutch connection with said shaft and serving to hold the crown cage and dial in operative relation with the shaft, a pawl carried by the cage for engagement with said ratchet, and a releasable locking device for holding the ratchet to said shaft but permitting its removal therefrom, whereby the crown cage and selecting dial may be removed.

4. In apparatus for feeding crowns, and

in combination, a hopper, means for forming an annular storage channel carried by said hopper, a rotatable hopper shaft, a crown cage and selecting mechanism, rotatable within said storage channel, a ratchet, a clutch connection between said ratchet and the hopper shaft, a pawl on the cage for engagement by said ratchet, a locking plate on the front of the ratchet having a portion cut out and bent away to leave a pear-shaped opening, the shaft having a groove for receiving the smaller end of said opening, thereby detachably holding the ratchet to the shaft, and means for retaining the locking plate in position.

In testimony whereof, I have hereunto set my hand.

CONSTANT J. KRYZANOWSKY.
